(57) **CLAIM**

The ornamental design for a chair, as shown and described.

DESCRIPTION

FIG. 1 is a front right perspective view of a first embodiment of a chair showing our new design;

FIG. 2 is a rear right perspective view thereof;

FIG. 3 is a front elevation view thereof;

FIG. 4 is a rear elevation view thereof;

FIG. 5 is a right side elevation view thereof, the left side view being a mirror image;

FIG. 6 is a top plan view thereof;

FIG. 7 is a front right perspective view of a second embodiment of a chair showing our new design;

FIG. 8 is a rear right perspective view thereof;

FIG. 9 is a front elevation view thereof;

FIG. 10 is a rear elevation view thereof;

FIG. 11 is a right side elevation view thereof, the left side view being a mirror image; and,
